UNITED STATES PATENT OFFICE.

JOSEPH HENRY MACK, OF PASSAIC, NEW JERSEY.

DESIGN FOR A TEXTILE FABRIC.

Application filed June 8, 1928. Serial No. 27,045. Term of patent 3½ years.

To all whom it may concern:

Be it known that I, JOSEPH HENRY MACK, a citizen of the Republic of Poland, residing at Passaic, in the county of Passaic and State of New Jersey, have invented a new, original, and ornamental Design for Textile Fabric, of which the following is a specification, reference being had to the accompanying drawings, forming a part thereof.

The figure is a plan view of a section of the textile fabric embodying my new design.

I claim:

The ornamental design for a textile fabric, as shown.

JOSEPH HENRY MACK.
